PORTABLE FOLDING TABLE WITH LOCK MEANS

Harold R. Nielsen, Mendota, Minn.

Application January 2, 1953, Serial No. 329,171

2 Claims. (Cl. 311—104)

This invention relates to an improvement in portable folding tables wherein it is desired to provide a table which may be folded up and stored in a relatively small space when not in use.

Many churches, schools and auditoriums have rooms which are used for eating purposes from time to time, but ordinarily are used for other purposes. For example, many schools and churches have gymnasiums and assembly rooms which normally serve one purpose, but which may be used from time to time for banquets, dinners, luncheons and the like. Various types of tables have been constructed which may be used for purposes of this type. Most such tables are not readily portable and require the services of at least two persons in putting up the table or putting it away.

An object of the present invention lies in the provision of a sectional table which includes a plurality of sections hingedly connected together and in supporting these sections in such a way that they may be easily folded by one person. As a result a table which is of sufficient size to comfortably seat several persons may be folded and put away by a single person without difficulty.

A feature of the present invention lies in the provision of a table including a pair of sections which are hingedly connected at the center. Each individual section is supported by a leg unit which is of the self-supporting type so that the leg unit will remain in vertical position regardless of the position of the top. By folding the two sections upwardly at their hinged joint and by moving the leg units of the two sections together, the table may be quickly and easily folded and rolled into a storage position.

A further feature of the present invention resides in the provision of a sectional table in which each section is supported by a leg unit which is hingedly connected to the table top at a point intermediate the ends thereof. As a result the ends of the table tend to counter-balance the center portion of the table, making the table easily foldable by one person.

A further feature of the present invention resides in the provision of a sectional table including two pivotally connected table sections which are foldable from a common plane to a substantially parallel relation and in supporting each section by a self-sustaining leg section which may be folded into overlapping relation with another leg section. In other words, when the two leg sections fold together a portion of one unit telescopes with the portion of the other unit so that the leg units may fold into close proximity.

A further feature of the present invention lies in the provision of a portable sectional table including a pair of table top sections hingedly connected together and each supported by an individual leg unit. A central leg is connected between the two table sections and is foldable into supporting position when the two sections are on a common plane and is foldable between the two sections when the sections are folded into pivotal parallel relation. Braces are provided which connect the central leg unit to each individual section, and a locking means is provided for holding the braces in a predetermined relation to the central leg. These braces may

2

therefore hold the table in flat condition so that the table tops can not tilt out of horizontal position when the lock is in place.

These and other objects and novel features of my invention will be more clearly and fully set forth in the following specification and claims.

In the drawings forming a part of the specification:

Figure 1 is a side elevational view of a portable sectional table showing in general the construction thereof.

Figure 2 is a top plan view of the table showing in dotted outline the general position of the leg units.

Figure 3 is a side elevation view of the table when the table top sections are folded into generally parallel relation.

Figure 4 is an elevation view of the table at right angles to the view shown in Figure 3.

Figure 5 is an end elevation view of the table in set up condition.

Figure 6 is an enlarged detail view showing the central leg section and the manner in which it is connected to the two table top sections.

Figure 7 is an elevation view of a detailed portion of the locking mechanism between the central leg section and the braces connecting this section with the table tops.

Figure 8 is a side elevation view of a modified form of table.

Figure 9 is a top plan view of this construction.

Figure 10 is a front elevation view of the table in folded condition.

Figure 11 is a side elevational view of the modified form of table in partially folded position.

Figure 12 is a sectional view through a portion of the table, the position of the section being indicated by the line 12—12 of Figure 8.

Figure 13 is a sectional view through a portion of the construction, the position of the section being indicated by the line 13—13 of Figure 12.

The portable foldable table is indicated in general by the letter A. As illustrated in Figure 1 of the drawings, the table includes a pair of table tops 10 and 11. A cross member such as 12 is preferably provided beneath the abutting edges of the two top sections. Hinges 13 and 14 connect the cross member 12 to the two top sections 10 and 11 to pivotally connect these two table tops.

The leg unit illustrated in general by the numeral 15 is hingedly connected at 16 to the table top 10. A similar leg unit 17 is hingedly connected at 19 to the table top 11. Both of the leg units are similarly constructed and both leg units are self-supporting to the extent that each leg unit remains in upright position regardless of the position of the table tops.

The specific details of construction of the leg unit may vary somewhat depending upon the particularly type of material which is to be used to form these units. In the particular construction illustrated, each leg unit comprises a series of tubular members which are bent to form the desired support. For example, the leg unit 15 illustrated in Figure 5 of the drawings is shown as having a top transversely extending tubular member 20 which is bent at each of its ends 21 and 22 to form downwardly and inwardly diverging brace portions 23 and 24 respectively. The brace portions 23 and 24 are bent to provide parallel portions 25 and 26 which may be spot welded or otherwise secured together. The lower ends of the parallel portions 25 and 26 are bent to diverge downwardly and outwardly as indicated at 27 and 29.

The leg unit 15 also includes a transverse cross brace 30 which is bent downwardly at its ends as indicated at 31 and 32. The lower extremities of the downwardly extending portions 31 and 32 are bifurcated to provide notches 33 and 34 respectively for accommodating rollers 35 and 36. A pivot pin 37 may extend through the bifurcated lower end of each leg and through the roller

70

3

35 to provide a pivotal support therefor. Alternatively, casters may be inserted in the tubular lower ends of each leg.

The lower extremities of the downwardly diverging portions 27 and 29 are spot welded or otherwise secured to the cross member 30 in the manner illustrated in Figure 5. All of the parts of the construction described to this point are substantially in a common plane when the leg unit is viewed from the side.

In order to make each of the leg units self-sustaining, a longitudinally extending member is secured to each cross member 30. The leg unit 15 is provided with a longitudinally extending member 39 which is provided with two down-turned ends 40 and 41 which are either bifurcated to accommodate rollers 42 and 43, or else are socketed to accommodate casters. The leg unit 17 is similarly provided with a longitudinally extending brace member 44 which is provided with down-turned ends 45 and 46 which are bifurcated to accommodate rollers 47 and 49, or else are socketed to accommodate casters. Thus it will be seen that in each leg unit, rollers are provided forwardly and rearwardly of the plane of the central portion of the leg unit so that each leg unit is self-sustaining and will remain in an upright position at all times.

From Figures 3, 4, and 5 of the drawings, it will be seen that the longitudinally extending leg unit member 39 is positioned on one side of the transverse center of the table, while the other longitudinally extending member 44 of the leg unit 17 is secured to its leg unit on the other side of the transverse center of the table. As a result, when the two leg units are moved toward one another, the members 39 and 44 will telescope or will overlap so that the upright portions of the two leg units may be moved relatively close together.

The center leg unit is indicated in general by the numeral 50. This center leg unit includes a vertical post 51 which is anchored at its upper end to the cross member 12 which is hingedly connected to the table tops. Inclined braces 52 and 53 are secured to the post 51 near its upper extremity and extend upwardly and outwardly to be secured in the cross member 12 at points laterally spaced from the center post 51. At the lower extremity of the center post 51 is provided a roller supporting member 54 which is identical to the roller supporting members 30 of the leg units 15 and 17. In other words, the cross member 54 extends laterally of the table and is bent downwardly at its extremity to engage the floor. The ends of the cross member 54 may be provided with rounded extremities to merely slide upon the floor, or may support rollers or casters in the manner of the other leg units. However, as the central leg unit is usually out of contact with the floor when the table is being moved to any extent, the casters and rollers are not of great importance at this point.

As illustrated in Figures 6 and 7 of the drawings, a collar 55 is slidably supported upon the post 51 for vertical movement thereupon. A pair of spaced ears 56 extend from one side of the collar 55 and a second pair of spaced ears 57 are arranged on the opposite side thereof from the ears 56. The ears 56 are spaced sufficiently to accommodate a brace 59 therebetween which is pivotally connected to the ears at 60. The ears 57 are likewise spaced sufficiently to accommodate a brace 61 which is pivotally connected to the ears at 62. A pair of spaced ears 63 project downwardly from the table top 10 and a similar pair of ears 64 extend downwardly from the table top 11. The brace 59 extends between the ears 63 and 66. Thus the collar 55 is hingedly connected to a brace 66. The brace 61 extends between the ears 64 and is pivotally connected thereto at 65. The brace 61 is pivotally connected thereto at 66. The brace 61 is pivotally connected to the ears 57.

As best indicated in Figure 7 of the drawings, an additional pair of ears 67 extend from the collar 55 at right angles to the ears 56 and 57. A locking lever 69 is hingedly connected at 70 between the ears 67. The lock-

ing lever 69 is provided with an angularly extending end 71 which is designed to extend into a recess or socket 72 in the post 51. A spring 73 normally biases the locking lever 69 into locking position. Obviously, the locking lever may be disconnected from the socket 72 by pivoting the lever in a clockwise direction about the pivot 70 against the tension of the spring 73.

The table thus described may pivot between two extreme positions, one of which is illustrated in Figure 1 of the drawings, and the other of which is illustrated in Figures 3 and 4 thereof. When the table is in the position illustrated in Figure 1, the table top sections 10 and 11 are arranged in a common plane and the leg units 15, 17, and 50 are in vertical parallel relation. The braces 59 and 61 are so arranged as to hold the central leg unit in a vertical position and when the table tops are horizontal, the locking lever extremity 71 is engaged in the socket 72.

With the collar 55 thus locked from movement upon the central leg unit, the two table top sections are locked from hinging movement. This feature is important as the leg units 15 and 17 are preferably hinged at a point considerably spaced from the ends 74 and 75 of the table top sections 10 and 11. The over-hanging ends of the table top sections act to at least partially counter-balance the weight of the table top portions between the leg units 15 and 17 so as to permit the easy folding of the table when the locking lever is released.

When it is desired to fold the table into an operative form, the locking lever 69 is released so that the collar 55 may move longitudinally of the post 51. By raising upwardly on the center portion of the table, the table top section 10 will hinge in one direction and the table top section 11 will hinge in the opposite direction so that the joint between the table tops moves upwardly. As indicated in Figure 4 of the drawings, the two table tops 10 and 11 may fold into substantially parallel relation in folded condition. In this position the extremity 71 of the locking lever 72 may engage in a second aperture 76 in the post 51 to hold the structure folded. The table will then remain in the folded condition illustrated in Figures 3 and 4 of the drawings until the locking lever is disengaged.

It will be noted that as the table leg supports 15 and 17 move toward one another, the longitudinally extending members 39 and 44 overlap to permit the leg units to move into close relationship. This feature is also of importance as it permits the leg units to be stable and at the same time permits the table to be stored in a relatively small space.

In Figures 8 through 13 of the drawings, I disclose a modified form of table construction which has certain features of advantage over the previously described construction. As described, each table section of the table A is supported by four casters. In the event the floor on which the table is supported is somewhat uneven, the four casters may not all rest upon the floor simultaneously, causing the table to rock slightly. The table B is in many respects similar to the previously described construction, but has the advantage that each table section is supported upon a portable support mounted upon three spaced casters or rollers.

The table B includes a pair of table top sections 79 and 80 which are shown as being generally rectangular in form. The section 79 is connected by a hinge 81 to a center transverse support 82. The table top section 80 is also connected to the central support 82 by a hinge 83. The hinges 81 and 83 extend in parallel relation so that the two sections may hinge simultaneously.

The table top section 79 is provided with a transverse support 84 which is hingedly connected to the section 79 by the hinge 85. A standard 86 extends downwardly from the transverse support 84 and is connected at its lower extremity between a pair of curved arms 87 and 89. As indicated in Figure 9 of the drawings the curved

arms 87 and 89 are connected together at their forward extremity as indicated at 90 and diverge apart so that the other ends of the arms are spaced apart a substantial distance. Casters 91 and 92 are provided at the extremities of the arms 87 and 89 and a third caster 93 is supported near the juncture 90 of these arms. As indicated in Figure 9 of the drawings, the arms are not centered. The joined ends 90 thereof being to one side of the longitudinal center of the table top sections.

The top section 80 is hingedly secured at 94 to a cross brace 95 which is located at the upper extremity of a standard 96. The standard 96 is supported by a pair of curved arms 97 and 99 as illustrated in Figure 9. One end of each arm extends into substantial contact with the other arm forming an integral end 100. The other ends of the arms diverge apart and support casters 101 and 102 at their extremities. The joined ends 100 of the arms also support a third caster 103.

It will be noted that the joined ends of the arms and the leg structure is off-set from the longitudinal center of the table tops, the leg unit supporting the section 79 being on one side of the longitudinal center and the other leg unit supporting the section 80 being on the opposite side of the longitudinal center.

A pair of ears 105 extend downwardly from the table section 79 in spaced relation and act to support a brace arm 106 therebetween. A similar pair of ears 107 project downwardly in spaced relation from the table top section 80 to a supporting brace arm 109 therebetween. The two brace arms 106 and 109 are pivotally connected together at their other extremities as indicated at 110.

A lug or ear 111 is mounted upon the brace arm 106 and a similar lug or ear 112 is provided on the brace arm 109. A link 113 is pivotally connected to the lug 111 and a similar link 114 is pivotally connected to the lug 112. The two links 113 and 114 are pivotally connected at their other extremities as indicated at 115. As indicated in Figures 12 and 13 of the drawings, means is provided for locking the table sections in alignment. A mounting plate 116 is secured to the transverse member 82 by screws 117 or other suitable means and this base plate supports a downwardly opening socket member 119. A lug 120 extends downwardly from the mounting plate 116 at a point spaced from one end of the socket 119. A slideable latch bolt 121 extends through the lug 120 and through one side of the socket 119. A spring 122 is interposed between a fixed washer 123 on the latch bolt 121 and the lug 120 to urge the latch bolt into the socket 119.

The links 113 and 114 are provided with flattened ends 124 and 125 which are apertured to receive a tubular grommet or rivet 126 which holds the links pivotally connected together. A spacing washer 127 is provided between the ends 124 and 125 to permit free pivotal motion of the links. The rivet or grommet is provided with enlarged ends so that the links may pivot with respect to one another about the axis of the rivet.

In operation when the table is in use the table top sections 79 and 80 are on a common plane as indicated in Figure 8. In this position the brace arms 106 and 109 converge together at a point below the center cross member 82. The links 113 and 114 extend upwardly so that the upper ends of these links enter into and are engaged by the socket 119. In entering the socket the relative movement between the socket and the knee joint between the links 113 and 114 acts to retract the latch bolt 121 against the tension of the spring 122 and the tapered end of this latch enters into the interior of the tubular rivet 126 to hold the knee joint engaged in the socket 119.

When it is desired to fold the table so that it may be readily placed in storage, it is only necessary to retract the latch bolt 121 and exert the upward force at the center of the table. This acts to withdraw the links 113 and 114 from the socket 119. The top sections 79 and 80 pivot about their hinges 85 and 94 respectively, the 75

center connected portion of the table raising upwardly and the outer ends of the table sections folding downwardly toward their supporting standards 86 and 96. During this action the distance between the standards 86 and 96 must decrease and the standards roll toward one another.

Due to the fact that the two standards are off-set from the longitudinal center of the top sections, the joined ends 90 of the arms 87 and 89 may extend past or alongside of the joined ends 100 of the arms 97 and 99 so that the two carriages which support the standards may telescope. As a result the standards 86 and 96 may fold into close relationship in the folded position of the structure. During this operation the braces 106 and 109 fold downwardly and the links 113 and 114 fold toward side by side relation.

It is recognized that the complete table is supported upon six rollers or casters. However, each individual carriage is supported upon three rollers or casters so that each carriage is at all times resting upon the floor at three spaced points, thus firmly supporting the connected top section. Because of the length of the top sections, there is of necessity a certain slight flexibility or resilience between the sections and accordingly both carriages will rest firmly upon the floor unless the floor is extremely uneven.

In accordance with the patent statutes, I have described the principles of construction and operation of my portable folding tables, and while I have endeavored to set forth the best embodiments thereof, I desire to have it understood that obvious changes may be made within the scope of the following claims without departing from the spirit of my invention.

I claim:

1. A table including a pair of table top sections, means hingedly connecting said sections together, carriage means connected to each table top section and hingedly connected thereto along parallel hinges, a pair of brace arms pivotally connected together, one of said brace arms being pivotally connected to each table top section, a link pivotally connected to each brace arm, said links being pivotally connected together and extending upwardly from said brace arms, the pivotal connection between said links, and the means hingedly connecting said table top sections being in substantially a common plane, and cooperative means on said links and on said table top sections to limit pivotal movement of said table top sections in one direction.

2. The structure described in claim 1 and including a second cooperative means on said table top sections and on said links to lock said links and said table top section together in one position thereof.
